UNITED STATES PATENT OFFICE.

RUDOLPH CONRADER, OF ERIE, PENNSYLVANIA.

DEVICE FOR TREATING ARTESIAN WELLS.

1,123,690.

Specification of Letters Patent.

Patented Jan. 5, 1915.

Application filed February 27, 1912. Serial No. 680,334.

To all whom it may concern:

Be it known that I, RUDOLPH CONRADER, a citizen of the United States, residing at Erie, in the county of Erie and State of Pennsylvania, have invented new and useful Improvements in Devices for Treating Artesian Wells, of which the following is a specification.

This invention relates to devices for treating Artesian wells and consists in certain improvements in the construction thereof as will be hereinafter fully described and pointed out in the claims.

The invention is particularly adapted for treating oil wells. The "oil sand" in different territories varies greatly, but usually there is formed in the oil bearing sand an enlarged pocket from which the oil is pumped. This pocket is formed in various ways. Where the sand is very loose it may be formed by the mere operation of pumping. Where it is more dense, it is formed by shooting the well. In the after operation of the well, the walls of this pocket become incrusted or coated with paraffin, or other material forming the base of the oil and if permitted to accumulate seriously interferes with the production of the well.

This invention has two leading objects, one, to measure this pocket so that its dimensions may be known and from the information thus gained the well may be given intelligent treatment.

The second leading object is to remove the coating or incrustations on the walls of the pocket so as to increase the production from the well.

Other objects especially those relating to the details of construction will appear from the specification and claims.

The invention is illustrated in the accompanying drawings as follows:—

Figure 1 shows a well and pumping apparatus, partly in section. Fig. 2 is a plan view of the casing head. Fig. 3 a section on the lines 3—3 in Fig. 4. Fig. 4 a section on the line 4—4 in Fig. 3. Fig. 5 a section on the line 5—5 in Fig. 3. Fig. 6 is a section of a well with pumping apparatus shown therein, said apparatus being partly in section, the point of view being from the right of Fig. 1. Fig. 7 a section on the line 7—7 in Figs. 6 and 9. Fig. 8 a section on the line 8—8 in Figs. 6 and 9. Fig. 9 a section

on the line 9—9 in Fig. 7. Fig. 10 a side elevation of the nozzle joint, partly in section on the line 10—10 in Figs. 7 and 8. Fig. 11 a section showing the yielding catch for the nozzle, the section being on the line 11—11 in Fig. 12. Fig. 12 a plan view of the same parts, partly in section on the line 12—12 in Fig. 11. Fig. 13 a section on the line 13—13 in Fig. 1.

1 marks the well pocket, 2 the walls of the pocket, 3 the bore leading to the surface, 4 the casing in the bore, 5 the casing head and 6 the tubing. These are ordinarily found in oil wells.

The working barrel 7 is secured to the tubing. It is provided with the standing valve fitting 8 in which an ordinary standing valve (not shown) is placed for the pumping action. Below the standing valve fitting, the bypass check fitting 9 is secured to the standing valve fitting 8. The check 10 is arranged in this fitting, the check being arranged in the cage 11. Cross passages 12 lead from without the fitting to the passage 13 leading to the check 10. A bypass 14 is formed in the angles formed by the passages 12 so that liquid may pass down around the check valve but at the same time liquid may be pumped in through the check valve.

A nipple 15 is screwed into the lower end of the fitting 9, and the nozzle valve fitting 16 is screwed on to the lower end of the nipple 15. The nozzle valve is shown in detail in the enlarged section in Figs. 3, 4 and 5. It has a chamber 17 in the upper end and a concentric cylinder 18 supported about midway in the fitting and a bypass 19 around the cylinder 18, the bypass connecting the chamber 17 at the upper end with a chamber 20 at the lower end of the fitting. A passage 21 leads from the bottom of the chamber 20 and a valve seat 22 is arranged in this opening. The valve 23 operates on the seat 22 to control the opening 21. The valve 23 is carried by a piston 23^a. The piston operates in the cylinder 18. A cap or plug 24 is arranged in the upper end of the cylinder 18 and a spring 25 is arranged between the piston and the plug 24, the spring extending into a socket 26 in the piston, the socket being provided to give a greater length of spring. A chamber 27 is formed between the plug 24 and piston 23^a.

A passage 29 leads from the chamber 27, the outer end of the passage being closed by a plug 30. A vertical passage 31 extends upwardly from the passage 29, and this 5 passage is controlled by a valve 32. An opening 33 is arranged above the valve 32 and the stem 34 of the valve extends from this chamber. The stem has a shoulder 35 and the spring 36 is arranged around the 10 stem 34 and operates against the shoulder 35, the upper end of the spring having a base on the plug 37 in the upper end of the chamber 33. The plug has the perforations 38 so as to avoid trapping liquid in the 15 chamber 33. An eye 39 is arranged in the upper end of the stem 34 and a cable 40 is secured to this eye and extends upwardly through the casing to the top of the well. By means of this cable, the valve 32 may be 20 opened. A passage 41 extends laterally from the valve 32 to the outside of the fitting 16.

The operation of this nozzle valve is as follows: With the parts as shown in Fig. 4, 25 liquid from the tubing will be subjected to tubing pressure both in the chamber 20 and the chamber 27, the liquid having entered through the chamber 27 through the opening 28 and being trapped there by the closed 30 valve 32. With the liquid under pressure in the chamber 27, the valve 23 is maintained in a closed position by the action of this liquid on the piston together with the force of the spring 25. When, however, the valve 32 35 is opened, the liquid in the chamber 27 is discharged and the passage leading to the valve 32 being much larger than the opening 28, the incoming liquid does not affect the pressure materially. Under these 40 conditions, the pressure of the liquid on those parts of the piston and valve, outside of the valve seat 22 is sufficient to overcome the spring 25 and thus the valve 23 is opened. Immediately it is opened, the full bottom 45 surface of the piston is subjected to the pressure of liquid below it, thus maintaining it in an open position until the valve 32 is closed. It will be understood that the pressure of the liquid with the height of 50 several thousand feet at this point is something tremendous and that, therefore, a fluid actuated valve such as here shown, can be readily controlled and operated with the auxiliary valve without subjecting the connecting parts to the pressure or strain necessary to operate the main valve directly.

A pulley carrier 42 is arranged in the casing head 5 and secured therein by the usual screws 43. This pulley carrier is split as 60 indicated in the section in Fig. 1 so that it may be removed without removing the cable supported. Ears 44 extend upwardly from the carrier and the pulley 45 is journaled between these ears on the bolt 46. The cable 40 extends over the pulley 45 and on 65

to a drum 47. This drum is fixed on a shaft 48. The shaft is journaled in the bearing post 49. A crank 50 is provided for operating the drum 47. The drum has a series of perforations 52 in its end and the pin 51 70 is provided which extends through a perforation 51^a in the post 49. By means of the pin 51 extending through the post into the perforation 52, the drum may be locked and in this way the valve 32 locked in an open 75 position if desired. A nipple 53 is screwed into the bottom of the nozzle valve fitting 16 and the nozzle 54 is connected with the nipple 53 by means of the nozzle joint fitting 55. A perforated ear 56 is fixed on the 80 nozzle 54 and the cable 57 extends from this ear through the casing to the top of the well. The cable 57 extends through the guide passage 58, the bottom of the guide passage being rounded at 59 to prevent cutting or abrasion of the cable. The cable passes over the pulley 60, the pulley being journaled on a bolt 61, and the bolt being carried by the ears 62 on the carrier 42. The pulley 60 is provided with the graduations 63 so spaced as to indicate with relation to an index finger 63^a the outward movement of the nozzle.

In the drawings we have shown the nozzle thrown out in dash lines and have indicated 95 spaces 3, 6 and 9 as indicative of that number of feet from the axis of the well. The graduations on the pulley 60 are also marked so as to indicate the number of feet that the nozzle has been deflected. By placing the pulley with relation to the starting point, the outward swing on the nozzle to the point that it engages the wall of the pocket may be read from the graduations on the pulley and thus the distance of the wall 100 of the pocket from the axis determined. By rotating and elevating the tubing the pocket may be accurately plotted both for each horizontal section and the vertical section. The cable 57 extends from the pulley 110 60 onto the drum 64. This drum is fixed on the shaft 65, and the shaft is carried by the post 66. A crank 68 is provided by means of which the drum may be manipulated. A swivel plug 69 is arranged in the top of the tubing and this is provided with an eye 70. A hook 71 engages the eye 70 and the hook is carried by a swivel 72. Any hoisting apparatus (not shown) may be used in connection with the hook to elevate the tubing so as to carry the nozzle to different parts of the pocket as desired.

After the pocket has been plotted, the walls of the pocket may be thoroughly cleaned by throwing the nozzle out to the 125 right position to be in proper relation to the well to properly deliver its jet and by the previous plotting of the pocket, the proper positioning of the nozzle may be nicely controlled, the tubing being rotated 130

to get to all parts of the circumference and elevated to reach the different levels of the pocket. A handle 73 is fixed on the upper end of the tubing by means of which the 5 tubing may be turned for this purpose.

In order to maintain a connection between the tubing and the source of supply of oil for the jet as the tubing is turned and lowered or elevated, I have provided the following mechanism: An opening 74 extends through the swivel plug 69 and forms communication with the annular pocket 75 in the fitting 76. A nut 77 is provided for tightening the joint between the plug and 10 the fitting. A tubular swivel joint 78 is connected with the fitting 76 and the nipple 79 connects the swivel joint 78 with the inner member 80 of a telescopic connection, the outer member 82 of this connection having 15 a slip joint 81 formed upon it through which the member 80 slides. This telescopic connection is of sufficient size to permit of the lifting of the tubing to the height desired. The lower end of the member 82 20 is connected to a tubular swivel joint 83 and this swivel joint is connected to a pipe 84 leading to a source of supply, ordinarily a tank (not shown).

The details of the nozzle joint 55 are 30 shown in Figs. 7, 8, 9 and 10. The nipple 53 enters the fitting 85. This fitting has the reduced or flattened extension 86. A passage 87 is formed in the outer edges of this extension. A tapered opening extends 35 transversely through it and the tapered hollow plug 89 is arranged in the opening 88. The plug has the openings 90 through it so that there is communication between the passage 87 and the interior of the plug. 40 Plates 91 are arranged on the sides of the extension 86. They have the annular projections 92 which extend into the plug 89 and form a close connection between the plates 91 and the plug. The plates have 45 the passages 96 which communicate with the openings 95 in the annular shoulders 92. The plates are clamped on the plug by means of the bolt 93. The annular shoulders 97 are arranged on the inside of the 50 lower ends of the plates 91 and these extend into the opening 98 in the fitting 99. A bolt 100 extends through the opening formed in the annular shoulder 97 and clamps the plates on the fitting 99. It will be understood 55 that the fitting 99 is rigidly secured to the plates. A joint is formed between the tapered surfaces of the plug 89 and the opening 88. In order that this may be yieldingly held in place, a gasket 94 is arranged 60 around the plug 89 on the face of the extension 86 and the side plate 91 engages this gasket and thus yieldingly communicates pressure through the bolt 93 to the opposite plate which forces the plug 89 into 65 the tapered opening. In this way a joint

capable of sustaining the tremendous pressure to which this is subjected may be formed.

It will be understood that this apparatus is lowered into an oil well of several thousand feet and in order to prevent the accidental outward movement of the nozzle when the apparatus is raised or lowered, I prefer to provide a yielding stop for holding the nozzle in place. The nozzle has the 70 end 101 and the opening 102 being flared or bellied. A catch 103 (see Figs. 11 and 12) is journaled on the pin 104, the pin being carried in the posts 111. The catch 103 has a socket 105 arranged in it and the spring 80 106 extends from the pin 107 in the socket 105 to a pin 108, the pin 108 being arranged on the lever 109. When the nozzle is dropped down to place, it engages the catch 103 from the left side, as shown in Fig. 11, 85 and forces it toward the right sufficiently to permit the nozzle to slip to place when the catch resumes its upright position and thus locks the nozzle against return movement. The rearward movement of the catch 103 is 90 limited by the shoulder 110 on the lever 109. The lever 109 is pivoted on the pin 104. It has the crotched lever as shown in Fig. 12. The pin 113 extends across the end of the lever. A spring 114 extends from this pin 95 to a perforated projection 115 on the base 116. This base 116 is fixed in the end of a shield 117, the shield extending over the valve fitting 16. The shield has the opening 118 at one side through which the nozzle 100 may be swung. When the nozzle is pulled outwardly through the action of the cable 57, it swings the lever 109 against the tension of the spring 114. The spring 114 especially with the leverage as arranged while 105 it yieldingly holds the nozzle is such as to require considerable pressure to disengage the nozzle from the catch. On the other hand, the spring 106 is only of sufficient strength to return the catch to its position 110 so that the weight of the nozzle readily carries it past the catch 103. The downward movement of the lever 109 is limited by the shoulders 112 which engage the posts 111.

In operation, the sucker rods and standing valve of the ordinary well are removed and the plug 69 with the telescopic connection attached. Ordinarily the first operation would be to get the plot of the pocket and this is done as heretofore described by 115 reading the outward movement of the nozzle of the dial on the pulley 60 with the different positions on the nozzle both as to elevation and circumferential location. After the plotting is completed, the apparatus is then 120 preferably dropped to the bottom of the pocket and the nozzle swung out to proper position to direct the jet against the walls and is swung in and out so as to maintain 125 this proper position as the tubing is rotated 130

and the nozzle is rotated by means of the handle 73. After this level has been cleaned, the apparatus is lifted and this operation is repeated. In this way if the incrustation is quite thick, the different portions can be more readily removed and dropped into the bottom of the well. Not only that but better results may be accomplished by operating above the actual level of liquid in the well and in this way this may be accomplished with fewer intervening pumpings. It will be understood that by detaching the plug 69, the pumping apparatus may be readily inserted without removing the nozzle or other parts and the well pumped out as often as desired. The jet is thrown on and off through the action of the valve 23, the valve being fluid actuated and controlled by the auxiliary valve 32, as described the auxiliary valve being controlled by a cable 40 from the top of the well. This feature, that is, the control of the liquid for the jet so as to turn it off and on and utilize it only when the nozzle is properly directed is an important feature of the invention. This is particularly true in that in delivering liquid in the tubing some difficulty will be manifested if it is filled entirely from the tank by reason of the trapped air and gas. Ordinarily, as the sucker rod is drawn, the liquid that then fills the tubing may be permitted to remain in it so as to avoid this difficulty. It will be noted that the liquid as it is used is continuously supplied by the tank. The liquid is siphoned over the flexible joint if there is not sufficient head by reason of the tank. In any event there is a continuous supply and a continuous control.

It is believed that this apparatus in many sands would be very much more efficient than shooting the well in providing the pocket in that no part of the walls of the well are disturbed except those which are desirable.

By the term nozzle I wish to include any jet opening or vent for the jet in its broadest sense regardless of whether it projects from the tube connection or not.

What I claim as new is:

- 50 1. In a device for treating Artesian wells, the combination of a tube leading to the bottom of the well; means below the top of the well controlling the flow of liquid from the tube; devices operative at the top of the well for controlling said means; a nozzle connected with said tube for controlling a jet against the side walls of the well; and mechanism for varying the position of the nozzle.
- 60 2. In a device for treating Artesian wells, the combination of a tube leading to the bottom of the well; means below the top of the well controlling the flow of liquid from the tube; devices operative at the top

of the well for controlling said means; a nozzle connected with said tube for controlling a jet against the side walls of the well; and mechanism for moving the nozzle circumferentially.

3. In a device for treating Artesian wells, 70 the combination of a tube leading to the bottom of the well; means below the top of the well controlling the flow of liquid from the tube; devices operative at the top of the well for controlling said means; a nozzle connected with said tube for controlling a jet against the side walls of the well; and mechanism for varying the level of the nozzle.

4. In a device for treating Artesian wells, 80 the combination of a tube leading to the bottom of the well; means below the top of the well controlling the flow of liquid from the tube; devices operative at the top of the well for controlling said means; a nozzle connected with said tube for controlling a jet against the side walls of the well; and mechanism for varying the level and moving the nozzle circumferentially.

5. In a device for treating Artesian wells, 90 the combination of a tube leading to the bottom of the well; means below the top of the well controlling the flow of liquid from the tube; devices operative at the top of the well for controlling said means; a nozzle connected with said tube for controlling a jet against the side walls of the well; mechanism for varying the position of the nozzle; and means for varying the direction of said nozzle.

6. In a device for treating Artesian wells, the combination of a tube leading to the bottom of the well; means below the top of the well controlling the flow of liquid from the tube; devices operative at the top 105 of the well for controlling said means; a nozzle connected with said tube for controlling a jet against the side walls of the well; mechanism for varying the position of the nozzle; and means for varying the direction and position of said nozzle in the well.

7. In a device for treating Artesian wells, the combination of a tubing; a working barrel on the tubing; a nozzle supported below 115 the working barrel; and means operative from the top of the well for controlling the movement of the fluid to the nozzle.

8. In a device for treating Artesian wells, the combination of a tubing; a working barrel on the tubing; a nozzle below the working barrel; and means operative from the top of the well for varying the position of the nozzle.

9. In a device for treating Artesian wells, 125 the combination of a tubing; a working barrel on the tubing; a nozzle below the working barrel; means operative from the top

of the well for varying the position of the nozzle; and devices for controlling the flow of liquid from the tubing to the nozzle.

10. In a device for treating Artesian wells, the combination of a tubing; a working barrel; a bypass check below the working barrel permitting the flow of liquid from the well to the working barrel and permitting the flow of liquid downwardly past the check; and a nozzle below the check.

11. In a device for treating Artesian wells, the combination of a tubing; a working barrel; a bypass check below the working barrel permitting the flow of liquid from the well to the working barrel and permitting the flow of liquid downward past the check; a nozzle below the check; and devices operative from the top of the well for controlling the flow of fluid to the nozzle.

20 12. In a device for treating Artesian wells, the combination of a tubing; a working barrel; a bypass check below the working barrel; permitting the flow of liquid from the well to the working barrel and permitting the flow of liquid downwardly past the check; a nozzle below the check; and means operative from the top of the well for changing the position of the nozzle.

13. In a device for treating Artesian wells, the combination of a tubing; a working barrel; a bypass check below the working barrel permitting the flow of liquid from the well to the working barrel and permitting the flow of liquid downwardly past the check; a nozzle below the check; and means operative from the top of the well for controlling the flow of fluid to the nozzle.

14. In a device for treating Artesian wells, the combination of a tubing; a nozzle supported at the lower end of the tubing; a valve controlling the flow of fluid from the tubing to the nozzle; and fluid actuated mechanism for controlling the valve.

15. In a device for treating Artesian wells, the combination of a tubing; a nozzle supported at the lower end of the tubing; a valve controlling the flow of fluid from the tubing to the nozzle; fluid actuated mechanism for controlling the valve; and devices for controlling said mechanism from the top of the well.

16. In a device for treating Artesian wells, the combination of a tubing; a nozzle carried at the lower end of the tubing; a valve controlling the flow of fluid from the tubing to the nozzle; a piston actuating said valve, said piston being normally balanced; and an auxiliary valve for relieving pressure at one side of the piston when it is desired to actuate the valve.

17. In a device for treating Artesian wells, the combination of a tubing; a nozzle carried at the lower end of the tubing; a valve controlling the flow of fluid from the

tubing to the nozzle; a piston actuating said valve, said piston being normally balanced; an auxiliary valve for relieving pressure at one side of the piston when it is desired to actuate the valve; and means leading to the top of the well for operating said auxiliary valve.

18. In a device for treating Artesian wells, the combination of a tubing; a nozzle mounted at the lower end of the tubing; and a yielding lock for holding the nozzle in position.

19. In a device for treating Artesian wells, the combination of a tubing; a nozzle mounted at the lower end of the tubing; and a yielding lock for the nozzle arranged to more readily yield with the movement of the nozzle in a resetting direction than in a disengaging direction.

20. In a device for treating Artesian wells, the combination of a tubing; a nozzle mounted at the lower end of the tubing; and a yielding lock for the nozzle comprising a yielding catch having a limited movement on a yielding lever whereby the nozzle moves to engaging position by the movement of the catch and it is disengaged by the movement of the lever and catch.

21. In a device for treating Artesian wells, the combination of a tubing; a nozzle movably mounted on the tubing; devices operative from the top of the well for actuating the nozzle; and means for indicating the amount of movement of the nozzle.

22. In a device for treating Artesian wells, the combination of a tubing; a nozzle movably mounted on the tubing; devices operative from the top of the well for actuating the nozzle; means for indicating the amount of movement of the nozzle; and mechanism for varying the level of the nozzle.

23. In a device for treating Artesian wells, the combination of a tubing; a nozzle movably mounted on the tubing; devices operative from the top of the well for actuating the nozzle; means for indicating the amount of movement of the nozzle; and mechanism for moving the nozzle circumferentially.

24. In a device for treating Artesian wells, the combination of a tubing; a nozzle movably mounted on the tubing; devices operative from the top of the well for actuating the nozzle; means for indicating the amount of movement of the nozzle; and mechanism for moving the nozzle vertically and circumferentially.

25. In a device for treating Artesian wells, the combination of a tubing; a nozzle connected with the tubing; a valve controlling the flow of fluid from the tubing to the nozzle; means operative from the top of the well for controlling the valve; devices oper-

ative from the top of the well for actuating the nozzle; and means for indicating the movement of the nozzle.

26. In a device for treating Artesian wells, the combination of a tubing; a nozzle connected with the tubing; a valve controlling the flow of fluid from the tubing to the nozzle; means operative from the top of the well for controlling the valve; devices operative from the top of the well for actuating the nozzle; means for indicating the movement of the nozzle; and means for varying the position of the nozzle.

27. In a device for treating Artesian wells, the combination of a tubing; a nozzle movably mounted at the lower end of the tubing; a cable for actuating the nozzle; a casing head; a split pulley carrier on the casing head; and a pulley in the carrier over which said cable operates.

28. In a device for treating Artesian wells, the combination of a tubing; a nozzle

pivottally secured to the lower end of the tubing; and a shield in which the nozzle may be housed when in alinement with the 25 tubing, the shield having an opening permitting the lateral swinging of the tubing.

29. In a device for treating Artesian wells, the combination of a tubing; a nozzle connected with the tubing; a casing through 30 which the tubing extends; a flexible connection for connecting the tubing with a source of fluid supply; devices for controlling the flow of fluid from the tubing to the nozzle; and means extending through the casing for 35 controlling said devices.

In testimony whereof I have hereunto set my hand in the presence of two subscribing witnesses.

RUDOLPH CONRADER.
